UNITED STATES PATENT OFFICE.

JOSEPH R. SWIFT, OF NEW ORLEANS, LOUISIANA.

RAILROAD-CAR COUPLING.

Specification of Letters Patent No. 26,303, dated November 29, 1859.

To all whom it may concern:

Be it known that I, JOSEPH R. SWIFT, of New Orleans, in the parish of Orleans and State of Louisiana, have invented a new and useful Improvement in Automatic Railroad-Car Couplings; and I do hereby declare that the following is a full, clear, and exact description of the same, reference being had to the accompanying drawings, 10 forming a part of this specification, in which—

Figure 1, is a longitudinal section of my improved automatic coupling, in the position for being brought into operation. Fig. 2, 15 is a similar section of the same as in operation. Fig. 3, is a plan view of the coupling in the same condition as represented in Fig. 2, and Fig. 4, is a front end view of one of the bumpers.

20 Similar letters of reference, in each of the several figures indicate corresponding parts.

Before stating my invention, I will premise by saying that I am aware that many 25 automatic car couplings have been patented and that the same principle which I have adapted in my coupling has been embodied in some of these, and that therefore I do not intend to cover by my patent, any new principle, but simply the embodiment of an old 30 principle in a new and improved organization of mechanism.

To enable others skilled in the art, to make 35 and use my invention, I will proceed to describe its construction and operation.

A, A', represent the bumpers or draw heads of two cars. The sockets B, B', of 40 these draw heads are made flaring at their front end in every direction, so as to readily admit the coupling link, D. These sockets are foreshortened from their top to near the center of their depth by means of horizontal shoulders a, a, and consequently are longer 45 from their front end to their rear ends, below said shoulders, than they are from their front to their rear ends, above the base of the shoulders. By thus constructing the sockets the deep portions f, f, in front of the shoulders a, a, are of sufficient size to readily 50 admit the link and allow the same considerable up and down play, but the shallow portions beyond said shoulders are just the same size as the link, and when the link enters the shallow portion g, of either of the

55 sockets it has no chance to play, and consequently remains in a horizontal position, or in such a position in the bottom of the bumper or draw head that the hook of an approaching or stationary car will certainly 60 strike the link in the right manner to insure a perfect coupling of the two cars together.

C, C, represent the elbow or lever hooks of the two draw heads. These hooks are attached to axial rods d, d, arranged at the 65 top and near the front of the bumpers or draw heads. The vertical portions m, of the hooks pass down through the slots b, c, the front side of the slot c, acting as a stop to the extremity of said portion of the hook, 70 and the slot b, providing room for the same to play backward when it is desired to effect an uncoupling of the cars, as illustrated in red in Fig. 1. The horizontal portion n of the elbow hook rests above the top of the 75 draw heads and extends back far enough to give a sufficient length of leverage to lift the hook out of the link or overcome the longitudinal strain upon the link when the cars 80 are in motion and safety requires a discontinuation of one or more cars of the train.

A weight or ball is provided on this lever end so that the hook will always have a 85 tendency to keep down in the link when the train is checked or when the longitudinal pull against the hook, from any cause, ceases. The front side of the vertical portion of the hook is made concave so as to insure a slipping of the link down under the hook when 90 it comes in contact with the same, and the rear side of the link, at its extremity, is made slightly convex so that it will more readily slip out of the link when the operation of uncoupling is being performed. 95

From the foregoing description, it will be seen that my invention is just the thing desired by rail-road companies; it being almost as simple as the common coupling pin, and yet free from the very great objection to 100 the same, viz: the necessity of men risking their lives in going between the cars to adjust it. It also possesses the very great advantage of providing sufficient leverage, in the hook itself, whereby the cars can be uncoupled while in motion or exerting longitudinal strain on the links by an upward pull of the train-hand and thus the power 105

of the train hand obtained, instead of only his weight as in lever links which are operated by a downward thrust.

What I claim as my invention and desire 5 to secure by Letters Patent, is—

The combination of the peculiarly constructed draw head A, B, f, a, q, b, c, with

the peculiarly constructed elbow shaped gravitating lever hook C, m, n, in the manner and for the purpose herein described.

JOSEPH R. SWIFT.
